Specification for Design.

Patented May 16, 1922.

Application filed October 10, 1921. Serial No. 506,885. Term of patent 3½ years.

To all whom it may concern:

Be it known that I, SEIZO KODAMA, a subject of the Emperor of Japan, and residing at San Francisco, in the county of San Francisco and State of California, have invented a new, original, and ornamental Design for Dolls, of which the following is a specification, reference being had to the accompanying drawing, forming part thereof.

Figure 1 is a front elevation of a doll showing my new design.

Figure 2 is a side elevation thereof and Figure 3 is a rear elevation of the same.

I claim:

The ornamental design for a doll, as shown.

SEIZO KODAMA.
